Patented Apr. 6, 1976

239,429

PORTABLE INSULATED CHEST

Dean W. Billingsley, Santa Ana, Calif.
(12001 Tacalene, Garden Grove, Calif. 92640)

Filed Sept. 13, 1974, Ser. No. 505,673

Term of patent 3½ years

Int. Cl. D7—07

U.S. Cl. D7—77

FIG. 1

FIG. 2

FIG. 3

FIG. 4

FIG. 5

FIG. 6

FIG. 1 is a rear perspective view of a portable insulated chest showing my new design;

FIG. 2 is a top view thereof;

FIG. 3 is a bottom view thereof;

FIG. 4 is an end view thereof;

FIG. 5 is a front view thereof; and

FIG. 6 is a rear view thereof.

I claim:

The ornamental design for a portable insulated chest, substantially as shown.
